WASTE RECEPTACLE

Robert W. Voorhees, Cedar Falls, Iowa, assignor to
Standard Manufacturing Company, Cedar Falls,
Iowa, a corporation of Iowa

Filed Dec. 20, 1967, Ser. No. 9,867

Term of patent 14 years

Int. Cl. D7—06

U.S. Cl. D49—30

FIG. 1 is a top, front perspective view of a waste receptacle showing a preferred form of my new design;

FIG. 2 is a side view thereof; and

FIG. 3 is a longitudinal sectional view through the waste receptacle as taken substantially along the line 3—3 in FIG. 2.

I claim:

The ornamental design for a waste receptacle, as herein shown and described.
